CONTAINER

Leo M. Harvey, La Canada, and Reuben Hill, Los Angeles, Calif.; said Hill assignor to said Harvey

Application June 23, 1939, Serial No. 280,819

9 Claims. (Cl. 62—91.5)

This invention relates to containers and relates more particularly to containers for refrigerated and perishable products. A general object of this invention is to provide a simple, inexpensive and particularly effective container adapted to be refrigerated by "dry ice" or solidified carbon dioxide.

In the co-pending application of Leo M. Harvey, Herbert Harvey and Reuben Hill, Serial No. 280,818 entitled "Device for providing refrigerants in containers," filed June 23, 1939, there is described and claimed a device for forming solidified carbon dioxide in outer containers to preserve or refrigerate products held in inner containers. The carbon dioxide is discharged under pressure by nozzles directed into the outer cartons or containers and the rapid expansion of the carbon dioxide results in a chilling effect which, in turn, causes solidification of the carbon dioxide. The solidified carbon dioxide builds up or accumulates on the surfaces of the containers so that the spaces or voids in the containers become filled with the solidified carbon dioxide. When employing typical containers a substantial part of the carbon dioxide leaving the nozzles at a high velocity strikes the surfaces of the containers and rebounds or glances off without adhering to the surfaces. This carbon dioxide that does not adhere to the container's surfaces usually does not solidify but remains gaseous and thus is lost.

Another object of this invention is to provide a container in which solidified carbon dioxide is to be formed that is designed and constructed in such a manner that there is little or no loss of the carbon dioxide by reason of the rebounding, or glancing off, of the incoming carbon dioxide under pressure.

Another object of this invention is to provide a container of the character mentioned embodying a wall structure or lining structure that is rough textured, foraminous, cellular, or broken in contour so that the solidifying carbon dioxide is retained on it and occupies its cells, crevices and pores to quickly build up or accumulate on the surface.

Another object of the invention is to provide a container for holding a food container in spaced relation to its inner walls leaving a space or spaces to receive discharge nozzles of a carbon dioxide dispensing device, said space or spaces being provided with multiplicities of pockets or recesses which hold the carbon dioxide for a long period, the carbon dioxide in the spaces serving as a refrigerant for the sealed food container

and the carbon dioxide being retained in the spaces and their many pockets or recesses upon gasification to act as an efficient insulator whereby the food may be preserved for a long period.

Another object of this invention is to provide a container of the character mentioned in which the rough textured cellular or uneven wall or lining parts are simple and inexpensive, and readily embodied in the container construction.

Another object of this invention is to provide a container of the character mentioned that is effectively insulated and that is light in weight and strong.

A further object of this invention is to provide a container of the character mentioned in which the wall or lining elements, providing for the effective retention of the carbon dioxide, strengthen the general construction and serve as thermal insulation to reduce heat absorption by the carbon dioxide.

The various objects and features of our invention will be fully understood from the following detailed description of typical preferred forms and applications of the invention, throughout which description reference is made to the accompanying drawing, in which:

Fig. 1 is a perspective view of one form of container of the invention with the top flaps of the outer container in the open position. Fig. 2 is a vertical detailed sectional view of the container illustrated in Fig. 1 with a portion of the inner container broken away to illustrate the character of the lining. Fig. 3 is an enlarged fragmentary horizontal detailed sectional view taken as indicated by line 3—3 on Fig. 2. Figs. 3A and 3B are fragmentary perspective views of the lining of the outer container. Fig. 4 is a perspective view of the container illustrated in Fig. 1 in the sealed or closed condition, and Fig. 5 is a side elevation of another form of container of the invention with the top flaps open and a portion broken away to illustrate the wall and lining structure in cross section.

The embodiment of the invention illustrated in Figs. 1 to 4 of the drawing may be said to comprise, generally, a container body 10, an insulating lining 11 in the body 10, a lining 12 within the lining 11 designed for the most effective adherence of the refrigerant, and an inner container 13 arranged in the body 10 and adapted to hold a perishable product.

The container body 10 may be of any shape and size and may be formed of any suitable material. In the case illustrated the body 10 is a rectangular structure formed of double-faced corrugated

board, paper or cardboard of the type commonly used in cartons, etc. The body 10 may be formed of a single piece of stock cut and folded to have sides 14 and top and bottom flaps 15. The bottom flaps 15 are folded in overlapping relation and are secured in a closed position by tape 16. The top flaps 15 may be initially left open, as illustrated in Fig. 1, for the reception of the inner container 13 and the carbon dioxide.

The lining 11 is a thermal insulation provided to reduce heat transference and the absorption of heat by the carbon dioxide. The lining 11 is not essential in every application of the invention. Where employed, the lining 11 may comprise a length of single or double faced corrugated paper board folded to have angularly related side parts lying against the inner surfaces of the body side walls 14. As best illustrated in Fig. 3 of the drawing the lining 11 in the form of the invention being described is constructed of double faced corrugated paper board or fiber board of the well known type. The lining 11 may include a bottom member 17 lying against the bottom flaps 15. The bottom member 17 may be formed of double faced corrugated paper board. It will be seen that the successive layers or thicknesses of the corrugated board provided by the body walls and the lining 11 form effective thermal insulation.

The lining 12 is an important feature of the invention. The lining 12 is provided to assure the most effective retention of the carbon dioxide on the interior of the outer container when the carbon dioxide is jetted or sprayed into the container so that the carbon dioxide accumulates as snow with a minimum gasification and loss. The lining 12 is arranged within the lining 11, where the latter is employed, and where the insulating lining 11 is dispensed with the lining 12 is arranged directly within the container body 10. In the preferred construction the lining 12 completely covers the inner sides of the lining 11 or the body walls 14 as the case may be. The lining 12 may be formed of any suitable or selected material. In the case illustrated it will be considered that the lining 12 is formed of paper, cardboard or other fibrous material. The lining 12 is formed or constructed to present roughened, ragged, frayed, cellular, broken or uneven surfaces against which the carbon dioxide impinges when discharged into the container and which operate to greatly reduce the deflection or bouncing of the carbon dioxide and thereby assure the accumulation or building up of solidified carbon dioxide within the container. The invention broadly contemplates the formation of the lining 12 in any selected or practical manner to give it the desired roughened, cellular or irregular surface.

In the construction being described the lining 12 is formed of single faced corrugated paper board. The illustrated lining 12 includes a plain outer sheet 18 adapted to lie against the lining 11 or the internal surfaces of the container sides 14 and a corrugated sheet 19 adhesively or otherwise secured to the inner side of the sheet 18. The corrugations of the sheet 19 preferably extend longitudinally or toward the upper and lower ends of the container body 10. In accordance with the invention the corrugations of the sheet 19 are interrupted, broken, cut or made irregular. In the arrangement illustrated the corrugated sheet 19 has transverse cuts or slots 20 of substantial width passing through its corrugations or ribs. The slots 20 may be simultaneously cut

or formed by a suitable cutting tool. The slots 20 are of substantial width so that the channels or grooves defined by the corrugations of the sheet 19 are fully open to the interior of the container at each slot 20 and are interrupted by the slots to constitute separate cells 21. It will be seen that the slots 20 cutting through the ribs or corrugations of the sheet 19 provide the corrugated sheet with a multitude of individual cells which communicate with the interior of the container. The slots 20 may be formed in such a manner that the fibers of the fibrous sheet 19 are frayed along their edges. The slots 20 are spaced throughout the entire lining 12 so that the entire inner surface of the lining presents a large number of spaced cells 21 and roughened or frayed edges at the slots.

The inner container 13 may be of any selected type and construction. In the case illustrated the container 13 is a cylindrical can or carton of the type commonly employed to hold ice cream, etc. and is sealed or closed by a suitable substantially tight cover. The inner container 13 fits the outer container 10 so that open spaces 22 of substantial capacity occur in the corners of the outer container. The inner container 13 is, of course, proportioned so that it may be entirely received in the outer container and so that it is held against shifting or dislocation.

In employing the improved container illustrated in Figs. 1 to 4, inclusive, the container 13 carrying the perishable product, is arranged within the outer container and the carbon dioxide is then discharged or injected under pressure into the outer container. The carbon dioxide may be discharged into the open corner spaces 22. The carbon dioxide under pressure discharged within the lining 12 strikes the surface of the sheet 19 which is irregular and broken by reason of the slots 20. The carbon dioxide enters the cells 21 and engages the frayed edges of the slots 20. The cellular formation of the lining 12 and the rough and irregular surface presented by the lining sheet 19 cause the carbon dioxide to remain on the lining and the retained or held crystalline carbon dioxide soon builds up on the lining. The carbon dioxide has little or no tendency to deflect or rebound from the rough, broken and irregular surfaces of the lining 12 and practically all of the carbon dioxide solidifies. When a sufficient quantity of solidified carbon dioxide has been formed in the container the top flaps 15 are closed and then sealed or held in the closed position by adhesive tape 23, or the like. The cells 21 serve to trap or hold the CO₂ when it returns to its gaseous state and this gaseous CO₂ forms a very efficient thermal insulation retarding the gasification of the main body or bodies of solidified CO₂.

The form of the invention illustrated in Fig. 5 of the drawing may be said to comprise, generally, an outer container body 10^a, a lining 12^a in the body 10^a, and an inner container 13^a in the body 10^a.

The body 10^a may be formed of paper, cardboard, or other suitable material. In the case illustrated the body 10^a is constructed of plain fiber-board, paper board, or the like, it being understood that the container body may be constructed of corrugated board, if desired. The lower end of the body 10^a is initially closed while the top flaps 15^a are initially open for the reception of the container 13^a and the refrigerant.

The lining 12^a is provided to insulate the container against excessive heat absorption by the

carbon dioxide refrigerant and to assure the efficient retention of the solidified carbon dioxide on the interior of the container. The lining 12^a comprises a layer of linters or other fibrous material applied to the inner surfaces of the container body 10^a. The fibrous material constituting the lining 12^a is preferably loose or open to have multitudes of small crevices, cells and spaces, and to present a rough or irregular surface. The fibrous lining 12^a may be applied to the internal surface of the body 10^a in any suitable or selected manner. In the case illustrated there is a layer 30 of adhesive tape or fabric on the interior of the container body 10^a to which the fibrous lining 12^a is applied. The fibrous material or fibers of the lining 12^a may be sprayed or blown on the adhesive layer 30 when the same is wet or tacky, or if desired, the fibers of the lining 12^a may be rolled onto the adhesive layer 30. The lining 12^a may be of substantial thickness to be efficient as a heat insulator. As illustrated, the lining 12^a may cover the inner surface of the container bottom and the inner surface of the large inner cover flap 15^a as well as the inner surfaces of the container body sides.

The inner container 13^a is provided to hold the perishable product to be refrigerated and is designed and proportioned to be held within the outer container body 10^a. The container 13^a may be of the same character as the container 13 and is adapted to fit snugly within the lining 12^a.

The container construction illustrated in Fig. 5 of the drawings has the same use and operation as the previously described form of the invention. The container 13^a is placed within the outer container body 10^a and the carbon dioxide under pressure is discharged into the open corner spaces of the container body 10^a. The carbon dioxide is readily held by the rough open surface of the fibrous lining 12^a and the solidified carbon dioxide or "dry ice" rapidly builds up in the container. There is little, if any, tendency for the carbon dioxide to deflect from or rebound from the rough porous surfaces presented by the loose fibers of the lining 12^a and practically all of the carbon dioxide solidifies to form an effective jacket of "dry ice" around the inner container 13^a. When a sufficient quantity of the carbon dioxide has been solidified in the outer container body 10^a the top flaps 15^a are closed and, if necessary, sealed shut.

Having described only typical preferred forms and applications of our invention, we do not wish to be limited or restricted to the specific details herein set forth, but wish to reserve to ourselves any variations or modifications that may appear to those skilled in the art, or fall within the scope of the following claims:

Having described our invention, we claim:

1. A container into which carbon dioxide under pressure is to be discharged to form dry ice comprising a container body, and a lining in the body

comprising a corrugated sheet whose corrugations are interrupted at spaced points along their lengths and at the internal surface of the lining to provide a multitude of cells for the retention of the carbon dioxide and edges that prevent the carbon dioxide from glancing off.

2. A container into which carbon dioxide under pressure is to be discharged to form dry ice comprising a container body, and a lining in the body comprising a corrugated sheet, the corrugations of the sheet having longitudinally spaced transverse slots with rough walls open to the interior of the body.

15 3. A container into which carbon dioxide under pressure is to be discharged to form dry ice comprising a container body, and a lining in the body comprising an adhesive material on the inner surface of the body, and a layer of fibers secured to the body by said adhesive to form a porous lining to which the carbon dioxide adheres.

20 4. A container into which carbon dioxide is to be discharged to solidify, the container comprising a container body, and lining means in the body presenting a multiplicity of frayed fibrous edges for holding the solid carbon dioxide.

25 5. A container into which carbon dioxide is to be discharged to solidify, the container comprising a container body, and lining means in the body having a plurality of cells and presenting 30 ragged fibrous edges at the mouths of the cells.

35 6. A container into which carbon dioxide is to be discharged to solidify, the container comprising a container body, and lining means in the body presenting a plurality of inwardly facing ridges, the ridges having spaced openings with frayed fibrous walls for holding the solid carbon dioxide.

40 7. A container into which carbon dioxide is to be discharged to solidify, the container comprising a container body, and lining means in the body including a wall of fibrous material having a multiplicity of rough walled openings providing ragged edges for the retention of the carbon dioxide.

45 8. A container into which carbon dioxide is to be discharged to solidify, the container comprising a container body, and lining means in the body including a corrugated fibrous sheet having 50 ragged cuts in its corrugations providing rough fibrous edges for the retention of the solidified carbon dioxide.

55 9. A container into which carbon dioxide is to be discharged to solidify, the container comprising a container body, and lining means in the body including a corrugated fibrous lining sheet, said sheet having a multiplicity of ragged slots interrupting its corrugations at longitudinally spaced points to provide cells and frayed fibrous edges for the retention of the solidified carbon dioxide.
